UNITED STATES PATENT OFFICE

2,027,793

NOZZLE FOR VACUUM CLEANERS

Victor Norris Morley Smith, Fergus, Ontario, Canada, assignor to Beatty Bros. Limited, Fergus, Ontario, Canada, a corporation of Canada

Application December 21, 1933, Serial No. 703,336
In Canada December 21, 1932

2 Claims. (Cl. 15—155)

In the renovation of carpets, rugs, tapestries and the like, it has become a common practice to use vacuum devices, which will rapidly draw a current of atmospheric air through the article carrying with it any dirt and dust which has accumulated in or on it; and it has been ascertained that by drawing atmospheric air over it close to the nozzle mouth, then forcing the air down and then upwardly between the lips of the nozzle into the vacuum device a better and quicker cleaning is attained.

The object of this invention is, therefore, to design a nozzle for a vacuum cleaner which will remove substantially all the dirt from a carpet, rug or the like by drawing a rapid current of atmospheric air over it in close proximity to the nozzle mouth, then down into it and then upwardly between the lips of the nozzle mouth of the vacuum device, especially in those types of rugs having a pile exposing the dirt which lies in the gutter and effecting its removal without any resistance being offered, the manner in which this is accomplished being understood by reference to the following description and the accompanying drawing in which:—

Fig. 1 is a front view of a vacuum device embodying this invention;

Fig. 2 is a plan view of the mouth of the nozzle;

Fig. 3 is a sectional view on the line 3—3
Fig. 1;

Fig. 4 is a fragmentary sectional view of the mouth of the nozzle; and

Fig. 5 illustrates the manner in which the mouth of the nozzle during operation separates the pile.

Like characters of reference refer to like parts throughout the specification and drawing.

In the drawing the vacuum device is shown in conjunction with a piece of carpet, this being all that is considered necessary to illustrate and describe the invention.

The vacuum device illustrated in Figs. 1 and 3 of the drawing is shown as having a vacuum chamber 1, in which is housed a fan (not shown) driven by an electric motor for creating the necessary suction, and a nozzle 2 having a nozzle mouth 3 in communication therewith for removing the dirt from the carpet and conducting it to the dirt collecting chamber associated with the cleaning device. The nozzle mouth 3 is provided with front and rear lips 4 and 5 respectively, each lip's lower extremity 4a and 5a respectively being tapered to a point throughout its entire length and one lip being at a different elevation

than the other. In Figs. 3, 4 and 5, I have shown the front lip 4, at a lower elevation than the rear lip 5 but the nozzle will work just as efficiently if the rear lip is the lower of the two.

As diagrammatically illustrated in Fig. 5, 6 indicates the weave of a rug, 7 the pile, and 8 the dirt gutter, the nozzle being assumed to travel in the direction indicated by the arrow and in so doing the front lip 4 exposing the dirt gutter to the action of the rapid current of air 10 which is being drawn into the suction chamber. The air current is as indicated by the arrows in Fig. 5, most of the air passing between the higher lip and the pile of the carpet to the nozzle mouth, thereby cleaning the surface and dirt gutter in the pile of the rug. The inrush of air into the nozzle mouth creates a lower pressure than atmospheric pressure, in the dirt gutter, exposed by the action of the lip 4 separating the pile, this lower pressure causing part of the 20 air passing under the higher side of the mouth or higher lip to be drawn into the dirt gutter whereby the dirt is lifted or carried into the dirt collecting chamber, only a very small volume of air passing upwardly through the weave. 25

Having thus fully described my invention what I claim as new and desire to secure by Letters Patent is:

1. A vacuum cleaner nozzle for cleaning carpets, rugs and the like having two parallel wedge shaped lips forming a substantially narrow mouth, one of said lips being at a higher elevation than the other lip, the higher positioned lip directing the flow of air before it enters the nozzle over the surface of the carpet in close proximity to the mouth of the nozzle and then down into the dirt gutter at the base of the pile and then upwardly between the lips of the nozzle to the dirt collecting chamber of the vacuum cleaner, the lower positioned lip penetrating the pile and spreading it as the nozzle is moved to and fro over the carpet. 35

2. A vacuum cleaner nozzle for cleaning carpets, rugs and the like having two lips forming a substantially narrow mouth, one of said lips being at a higher elevation than the other lip, said higher positioned lip being downwardly and inwardly inclined to direct the flow of air over the surface of the carpet in close proximity to the mouth of the nozzle and then down into the dirt gutter at the base of the pile and then upwardly into the nozzle. 45 50
